UNITED STATES PATENT OFFICE.

WILLIAM F. ZINK, OF GARRETT, INDIANA.

MEANS FOR LOCKING AUTOMOBILES.

1,327,366.

Specification of Letters Patent.

Patented Jan. 6, 1920.

Application filed November 14, 1917. Serial No. 201,978.

To all whom it may concern:

Be it known that I, WILLIAM F. ZINK, a citizen of the United States, residing at Garrett, in the county of Dekalb and State 5 of Indiana, have invented certain new and useful Improvements in Means for Locking Automobiles, of which the following is a specification, reference being had to the accompanying drawings.

10 This invention relates to means for locking automobiles to prevent the unauthorized use of the automobile, and particularly to devices of this nature in which communication is cut off between the fuel tank and the 15 carbureter in order to prevent the use of the automobile.

The general object of the invention is to provide a construction of this nature in which a plurality of valves are used, each 20 valve having to be turned to a predetermined position in order to establish communication through the line pipe extending from the tank to the carbureter, there being a dial in connection with each valve and a 25 pointer on the valve which, when moved to a predetermined position on the dial, causes the valve to shift to its open position.

A further object is to provide a construction of this kind in which a plurality of 30 pointers are used in connection with each dial, each pointer on each dial having distinguishing marks to thereby add to the permutations and combinations of which the locking device is capable.

35 A further object is to provide a construction in which ordinary stock valve bodies and valves may be used, thus minimizing the cost of the device.

40 A further object is to provide a device of this character in which a greater or less number of units, each comprising a valve and valve casing may be used, depending upon the make of car and other considerations.

45 Other objects will appear in the course of the following description.

My invention is illustrated in the accompanying drawings, wherein:

Figure 1 is a side elevation of my im- 50 proved locking device;

Fig. 2 is a top plan view thereof;

Fig. 3 is a section on the line 3-3 of Fig. 1;

Fig. 4 is a top plan view of one of the 55 annuli, carrying the pointers;

Fig. 5 is a top plan view of the valve.

Referring to these figures, it will be seen that my device comprises a plurality of valve casings, each designated 10. These valve casings are of an ordinary form and are connected by unions 11 or in any other suitable manner. Preferably these valve casings are detachably engaged with each other, though not necessarily so, as the valve casings might be made integral. These 65 valve casings are disposed in the pipe line 12 which leads from the gasoline tank to the carbureter of the engine. Disposed in each valve casing is a valve 13, which is preferably a rotatable valve having a dia- 70 metrically extending port 14, which, when the valve is turned in one direction, establishes communication through the valve and when turned in the other direction cuts off communication through the valve. 75

Disposed at one end of each valve casing is a dial 15. This dial is provided with radial graduations and certain of these graduations are lettered A, B, C, D, etc., there being minor graduations between each lettered graduation. These dials are secured in any suitable manner preferably by screws 15^a to a pair of longitudinally extending straps 16 so that the dials cannot rotate. Any other supporting means for the dials 85 may be used, however.

Attached to each valve stem 17 is an annulus 18 having a plurality of radially projecting pointers 19, shown as three in number, these pointers carrying different indicating characters, as for instance, the numerals 1, 2 and 3, if three pointers are used as shown in Fig. 4. Each annulus is engaged with a valve 13 to rotate therewith and to this end I have illustrated each valve stem as being screw-threaded for engagement by a nut 20, each valve being provided with an upwardly extending pin 21 engaging in a perforation made in the corresponding annulus 18. The nut 20 holds the 90 annulus in engagement with this pin. Each annulus 18 is also provided with a plurality of perforations for engagement with this pin 21 so that the annulus can be rotated with relation to the valve stem and engaged 95 at any desired point by the nut. The pointers 19 coact with the respective dials and move over the graduations thereof. Preferably the longitudinally extending braces 16 are connected to the assembled 100 105 110

valve bodies and braced by yokes 22 which extend beneath the valve bodies at opposite ends of the braces 16 and preferably, though not necessarily, the assembled valve bodies 5 will be braced from oscillation by means of an intermediate brace 23. The brace 23 has a foot 23^a, which is designed to receive suitable fastening means (not shown), for securing the brace on the casing of the engine 10 (not shown), at any suitable location, in order to support the series of valves, in order to prevent displacement thereof, and to insure rigidity.

The operation of this invention will be 15 obvious from what has gone before. When it is desired to prevent the unauthorized use of the car, any one or a plurality of the valves 13 may be rotated to a position to cut off passage through the pipe line, the 20 valve stem 17 being formed for engagement with a wrench for this purpose. Of course the valve stems might be provided with handles whereby they could be actuated. Now when it is again desired to use the car, 25 reference is made to the graduations on the dials and the valves are turned until a selected pointer on each valve stem points to a selected graduation mark on the dial. When all of the valve stems are disposed so that 30 the selected pointer on each stem points to a selected graduation on each dial, then the pipe line is opened and fuel flows to the carbureter. It is necessary, however, that every valve shall be turned to its proper position before this shall occur. Inasmuch as 35 there are a plurality of pointers coacting with each dial, it is obvious that one of these pointers must be selected and that because of this fact, any one ignorant of the combination 40 will not only have to consider the dial graduation to which a pointer must be directed, but the proper pointer which must be used. Thus, for instance, assuming that there are only two valves in the pipe line and 45 that there are fifty graduations on the dials, it will be obvious that with three pointers there will be 150 positions, which might be taken before a single valve would be opened and that with each additional valve, the 50 number of combinations and permutations which may be made is very greatly increased. At the same time any one understanding the combination can very readily turn the valves to their proper positions and, 55 in fact, only one or two of the valves need be turned from their proper positions in order to prevent unauthorized meddling with the car, as the person who is about to use the car will not know whether valves 60 are turned on or off. It will be seen that my device is formed, to a large extent, of stock materials, that these may be readily assembled so as to use two or more units as may be desired and that the device may 65 be used on cars of any ordinary motor.

Preferably the longitudinal bore of the valve bodies and the bore of each valve is larger in diameter than the pipe line, so that there will be no restriction or impediment to the free flow of the fuel from the tank to the 70 carbureter.

While I have illustrated a construction which I have found to be thoroughly effective and entirely practical, it will be understood that many minor variations may be 75 made therein without departing from the spirit of the invention as defined in the claims. It is to be noted that the yokes 22 and the parallel bars or straps 16 act to prevent accidental turning of the valve bodies. 80 This result is accomplished, since certain of the yokes straddle the connecting nuts between the valve bodies, to prevent turning of the nuts, while the straps or bars engage the upper faces of the valve bodies adjacent 85 their sides, thereby preventing turning of the bodies. The straps or bars not only hold the valve bodies against turning, but also constitute supporting means for the dial plates, there being securing means engaging through 90 the dial plates and into the straps or bars, to hold such parts securely connected. The provision of this means is very essential in a device of this kind not only to hold the valve bodies and the dial plates in position to 95 prevent their accidental turning, but also for holding them in axial alignment, and in this way, it is easier and more convenient to ascertain the reading of the dial plates. Since the upper faces of the valve bodies 100 are substantially flush and owing to the parallel straps holding them in such positions, it is very easy for an operator to adjust the pointers, according to the positions that may be desired.

Having described my invention, what I claim is:

1. In a device as set forth, the combination with a plurality of connected valve bodies having a passage therethrough, of a 110 plurality of valves mounted in said bodies, each adapted to control said passage, each valve being movable independently of any other valve and including a valve stem, a pair of elongated bars resting on the upper 115 faces of the valve bodies adjacent their side portions and being in parallelism, means straddling portions of the valve bodies and being secured to said bars, a plurality of dial plates, each disposed concentrically 120 with and rotatably receiving a part of the valve, means for securing the dial plates to the bars, the dial plate being graduated, a pointer mounted on each stem for rotation therewith and coacting with the graduations 125 of the respective dial plate, and means for detachably holding the pointer in engagement with the valve.

2. In a device as set forth, the combination with a plurality of connected valve 130

bodies axially alined and having a passage, of a pair of elongated bars arranged in parallelism and disposed on the upper faces of the valve bodies near their opposite sides, 5 a plurality of valves mounted in said bodies, each being movable independently and controlling said passage and having a valve stem, a plurality of dial plates, each disposed concentrically with and receiving a 10 part of the valve, means for securing the dial plates to said parallel bars to hold the dial plates in position, a pointer mounted on each stem for rotation therewith coacting with the dial plate, means interengaging between the pointer and the valve for holding the pointer against movement relative to the valve, and means on the stem for clamping the pointer in fixed position relative to axial movement of the stem. 15 20 3. In a device as set forth, the combination with a plurality of connected valve bodies axially alined and having a passage, of elements straddling portions of certain of the valve bodies, means on the upper 25 faces of the valve bodies, adjacent the sides of the valve bodies and securely connected to said elements, thereby holding the valve bodies uniformly alined and secure against accidental turning movement, a plurality of 30 valves mounted in the bodies, each being movable independently and controlling said passage and having a valve stem, a plurality of graduated dial plates, each disposed concentrically with and rotatably receiving a 35 part of the valve, a pointer on each stem for rotation therewith and coacting with the 40 graduations of the dial plate, means interengaging between the valve and the pointer to prevent movement of the pointer relatively to the valve, and means on the stem to clamp the pointer against the valve. 4. In a device as set forth, the combination with a plurality of connected valve bodies having a passage, of a plurality of 45 U-shaped elements straddling certain of the valve bodies to prevent turning thereof and

holding the valve bodies in axial alinement, a pair of bars arranged in spaced parallelism and resting on the upper ends of the valve bodies and being secured to the 50 ends of the U-shaped elements to additionally prevent turning movement of the bodies, a plurality of valves mounted in the bodies, each being movable independently and adapted to control said passage and having 55 a stem, a plurality of dial plates, each concentrically disposed with and rotatably receiving a part of the valve, means for securing the dial plates to the parallel bars, said dial plates being graduated, a pointer 60 on each stem to rotate therewith and co-operable with the graduations of the dial plates, a pin interengaging between the pointer and the valve to prevent movement of the pointer relatively to the valve, and 65 a member threaded on the stem to clamp the pointer against the valve.

5. In a device as set forth, the combination with a plurality of connected valve bodies having a passage, of means to hold 70 the bodies in axial alinement and against accidental turning movement of one relatively to the other, a plurality of valves mounted in said bodies, each being independently movable and capable of controlling said passage and having a stem, a plurality of graduated dial plates, each disposed concentrically with and rotatably receiving a portion of the valve, means for securing the dial plates to the holding 75 means, a pointer on each stem rotatable therewith and coacting with the graduations of the dial plate, and means for detachably holding the pointer in engagement with the valve. 80 85

In testimony whereof I hereunto affix my signature in the presence of two witnesses.

WILLIAM F. ZINK.
